UNITED STATES PATENT OFFICE.

ALWIN G. STEINMAYER, OF MILWAUKEE, WISCONSIN, ASSIGNOR TO LINE MATERIAL COMPANY, OF SOUTH MILWAUKEE, WISCONSIN, A CORPORATION OF WISCONSIN.

CIRCUIT MAKING AND BREAKING DEVICE.

Application filed January 10, 1925. Serial No. 1,587.

This invention relates to certain new and useful improvements in circuit making and breaking devices and refers more particularly to what may be termed as a mercury contactor, although it is to be understood that any liquid medium capable of performing the desired functions may be employed.

It is a general object of this invention to generally improve the operation and construction of contact making and breaking devices of the type described.

With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawing, I have illustrated two complete examples of the physical embodiment of my invention constructed according to the best modes I have so far devised for the practical application of the principles thereof, and in which:

Figure 1 is a side view of a contact making and breaking device constructed in accordance with my invention, parts thereof being broken away and in section to illustrate details of construction;

Figure 2 is a view, partly in top plan and partly in section, taken through Figure 1 on the plane of the line 2—2, and

Figure 3 is a view similar to Figure 1 of a slightly modified form of my invention in which the operation thereof is reversed.

Referring now more particularly to the accompanying drawing, in which like numerals designate like parts throughout the several views; the numeral 10 designates a base member of porcelain or other suitable non-conducting material having two concentric wells or mercury pots 11 and 12 separated by the walls of a cup shaped portion 13 centrally formed in the base with its upper or outer edge preferably positioned below the top surface 14 of the base proper.

The wells or pots are preferably cylindrical in form for convenience in manufacturing the base and the top surface 14 of the base is preferably cut away or indented along its edge communicating with the outer well 12 to provide a pouring lip 15 to facili-

tate the removal of the liquid medium 16 disposed in the wells. As clearly shown in Figures 1 and 3, the level of the liquid medium is below that of the edge of the cup-shaped portion 13, thus dividing the liquid into two bodies.

The wires 17 and 18 forming part of an electrical circuit, the continuity of which is adapted to be broken between the two bodies of liquid, are electrically connected with the liquid in the inner and outer wells, respectively. The line 17 is connected with the liquid in the inner well by a screw 19 inserted through the bottom wall 20 of the center well with its head 21 disposed therein, the screw being secured in place by a nut 22 and suitable cement 23 to form a mercury tight joint, the conductor 17 being electrically connected with the screw by a terminal nut 24. The conductor 18 is connected with the body of liquid in the outer well through a strip of conducting material 25, bent to conform with an extension or base 26 projected above the top surface of the base member with its lower end 27 extended into the body of liquid and its upper end 28 clamped in place by a bolt 29 extending through the projection and to which the end of conductor 18 is electrically secured by a terminal nut 30. The circuit in which the lines 17 and 18 are included is broken between the two bodies of liquid which are normally separated by the wall of the cup shaped portion 13.

The two bodies of liquid are adapted to be electrically connected to complete the continuity of the circuit in which they are included by a metal spider 31 which is preferably of inverted bowl or cup shape with its inside diameter greater than the outside diameter of the cup shaped member 13 and the walls of the spider extend to a depth sufficient to project into the liquid in the outer well when the spider is projected thereinto with its top closed wall 32 at a point adjacent the top of the cup shaped portion 13. Extended from the central portion of the spider is a projection or stud 33, the lower or outer end of which is on a plane substantially even with the lower edge of the support member which extends into the body of liquid in the inner well when the spider is in lowered position to thus effect the electrical bridging of the two bodies of liquid in the manner best illustrated in Figure 1. The

stud 33 normally rests on the head 21 of the screw forming the terminal for the line 17 with the liquid within the central well as evidenced by the disclosure in the drawing.

The spider 31 is actuated by a solenoid 34 which is supported from the projection 26 of the base member with its tubular core 35 in axial alignment with the concentric wells or pots, its lower flange or end 36 being secured 10 to the projection 26 by suitable bolts or other fastening means 37, and the ends of the solenoid coil being connected with a suitable source of electrical energy by conductors 38. The armature 39 for actuating the 15 metal spider is preferably of tubular form, although its construction may be of any suitable type, and is slidably mounted within the tubular core 35. The lower end of the armature is fixed to the spider which is held 20 by gravity in circuit completing position with the mass of the armature below the center of the magnetic force of the solenoid so that energization of the solenoid causes a 25 quick movement upwardly to tend to center its mass with respect to the center of magnetic force of the solenoid and quickly withdraw the metal spider from the liquid causing a quick break of the circuit, as will be apparent. In order to facilitate the movement 30 of the spider 31 into and out of the liquid, a plurality of air openings 40 are formed therein preferably by cutting through the upper peripheral edge thereof, as illustrated in the drawings.

The specific form of my invention just described is of that type where the circuit is normally completed when the solenoid 34 is disconnected from its source of energy and the continuity of the circuit broken 40 when the solenoid is energized. In that form of my invention illustrated in Figure 3, the operation is reversed, the spider 31, instead of being connected directly with the armature 39, is connected therewith by a 45 rod 41 around the upper end of which between the lower end 42 of the armature and the attaching flange 36 of the solenoid is coiled an expansible spring 43 which normally urges the spider to its position free 50 of the body of liquid as illustrated in Figure 3. In this form of my invention the mass of the armature is normally above the center of magnetic force of the solenoid and the armature is drawn downwardly into the hollow core 35 thereof, compressing the spring 43, to project the spider into the liquid 55 upon energization of the solenoid.

When conductors of the nature illustrated 60 are to be used in connection with street lighting systems, it is often necessary that they be designed to work over a voltage range of approximately 80 to 120 volts. This being the case the current flowing through the solenoid at 120 volts is considerably more 65 than the current flowing at 80 volts. This

accordingly means that the coil must be designed suitable for working on an 80 volt circuit and yet be able to stand up on 120 volts, which is accomplished by winding the solenoid with wire of sufficient size to give 70 strength at 80 volts and the current is limited when used in connection with 120 volts along any range of voltage by inserting an adjustable core 44 into the fixed core 35 from the top. The adjustable core is preferably 75 made from a length of steel tubing longitudinally split, as at 45, in order that it may tend to spread and have a sufficient frictional contact with the fixed core 35 that it will set 80 fixed at any point.

Accordingly, when the adjustable core is pushed into the solenoid all the way so that it just allows the metal spider to open the circuit, a maximum choking effect is obtained. This limits the current and in this manner 85 the current can be cut down on 120 volts to an even smaller value than that obtained on 80 volts.

The spider 31 and the contact member 33 carried thereby are preferably coated with 90 a copper, zinc or other suitable plating. This serves as a protective coating against corrosion and also tends to increase the mercury amalgam surface so that the electrical circuit is made and broken between mercury and mercury rather than mercury and metal. 95

What I claim as my invention is:

1. An appliance of the character described, comprising a plurality of concentric chambers each adapted to have a body of liquid therein, means incorporating the liquid within the chambers in an electric circuit, the continuity of which is normally broken between the bodies of liquid, an inverted cup-shaped member adapted to be 105 moved into the liquid in the outer chamber, and a part carried by the spider and adapted to be inserted into the liquid within the inner chamber when the spider is inserted into the liquid of the outer chamber to electrically bridge the bodies of liquid and complete 110 the circuit.

2. An appliance of the character described, comprising a plurality of concentric chambers each adapted to have a body 115 of liquid therein, means incorporating the liquid in the chambers with an electric circuit the continuity of which is normally broken between the bodies of liquid, an inverted cup-shaped member adapted to be 120 moved into the liquid in the outer chamber, a part carried by the spider and adapted to be inserted into the liquid within the inner chamber when the spider is inserted into the liquid of the outer chamber to electrically 125 bridge the bodies of liquid and complete the circuit, and means preventing the formation of air pockets in the interior of the spider member when in contact making position.

3. An appliance of the character de- 130

- scribed, comprising a chamber adapted to contain a body of mercury or other liquid, means incorporating the body of mercury or the like in an electric circuit, a member 5 adapted to be moved into the body of mercury or the like to complete the circuit in which the mercury or the like is included, a solenoid for actuating said member having a tubular core, and a split sleeve frictionally 10 engaged in the upper end of the core to adjust the solenoid for currents of different voltage.
4. An appliance of the class described, comprising a plurality of concentric chambers each adapted to receive a body of liquid, 15 means incorporating the liquid in the chambers with an electric circuit the continuity of which is normally broken between the bodies of liquid, a solenoid mounted above the 20 chambers and in axial alignment therewith,
- an armature, an inverted cup shaped spider fixed to the lower end of the armature and adapted to be moved into the liquid in the outer chamber, and a stud carried by the spider and insertable into the liquid in the 25 inner chamber substantially simultaneously with the insertion of the spider into the liquid of the outer chamber to electrically bridge the bodies of liquid, said spider having vent means therein to prevent the formation of air pockets in the interior of the spider.
5. In a device of the class described, comprising a solenoid having a tubular core, an armature adapted to be attracted thereby, 30 and a split sleeve frictionally engaged in the upper end of the bore to adjust the solenoid for currents of different voltage.

In testimony whereof I affix my signature.

ALWIN G. STEINMAYER.
